UNITED STATES PATENT OFFICE.

FRANK KUHN, OF DETROIT, MICHIGAN.

ELECTRICAL HEATER.

1,119,841.

Specification of Letters Patent.

Patented Dec. 8, 1914.

Application filed January 10, 1914. Serial No. 811,313.

To all whom it may concern:

Be it known that I, FRANK KUHN, a citizen of the United States of America, residing at Detroit, in the county of Wayne and

5 State of Michigan, have invented certain new and useful Improvements in Electrical Heaters, of which the following is a specification, reference being had therein to the accompanying drawings.

10 The invention relates to electrical heating units, and has more particular reference to the means for providing insulated supports for the resistor.

15 It is the object of the invention to obtain a construction which is inexpensive to manufacture, which is adapted to be variously fashioned to suit different conditions and which will provide thoroughly insulated, heat-resisting supports at as many 20 points as necessary in the length of the conductor.

In the drawings: Figure 1 is an elevation showing one construction of my heating element; Fig. 2 is an enlarged cross 25 section thereof; Fig. 3 is a cross section through a modified construction; Fig. 4 is a perspective view showing another modification; and Fig. 5 is a perspective view of one of the resistor supports detached.

30 A is the resistor which may be of any suitable construction, but is shown in the form of a wire coil.

B are supporting members for the resistor, preferably formed of sheet metal 35 stampings having an eye portion C and shank portion D, the latter being twisted into a transverse plane. To insulate the members B they are connected to a strip E, with mica or other suitable insulating ma-

40 terial F laid therebetween. Preferably, the strip E is formed of sheet metal and of a U-shaped cross section, and the shanks D are placed between the two plies of the strip with the insulation F arranged there-

45 between, as shown. The strip E and the shanks D are also preferably provided with complementary projections and indentations, such as the beads G and H, and which form an interlock. Thus, when the U-

50 shaped strip E is suitably compressed it will form a clamp for retaining all of the supporting members B in fixed position, while the insulation between the shanks D

and the strip E will prevent short circuiting.

In Fig. 1 a straight strip is represented with a plurality of supports B distributed along the length thereof. In Fig. 3 a pair of strips E and E' are arranged upon opposite sides of the supporting members B, 55 and engage oppositely-extending shanks D and D' thereof. In Fig 4 the strips E² are bent into circular form and the resistor A' extends back and forth across this circle, being engaged with the eyes C at different 60 points thereon. It is obvious that the strips E may be fashioned into various shapes to support the resistor in any position desired.

What I claim as my invention is,—

1. An insulated support for resistor, comprising a sheet metal member for engaging the resistor, having a shank portion bent into a transverse plane, a clamping member for embracing said shank member having an interlocking engagement therewith, and 70 insulating material arranged between said shank member and clamping strip.

2. An insulated support for resistor, comprising a longitudinally beaded metallic strip, a series of supporting members having 80 beaded shank portions for engaging said beaded strip, and insulating material between said shank portions and strip.

3. An insulated support for resistor, comprising a metallic strip of U-shaped cross 85 section, having complementary longitudinally-extending beads, a series of supporting members provided with shank portions having complementary beads and embraced by said U-shaped strip member, and insulating material clamped between said shank 90 portions and strip.

4. An insulated support for a resistor, comprising a sheet metal member for engaging the resistor, said member having 95 a shank portion provided with a lateral offset, a clamping member for embracing the shank portion of said member, and being provided with an offset portion complementary to that of the shank portion, an 100 insulating material arranged between said shank portion and clamping member, said shank portion, clamping member, and insulating material being locked in place by the engagement of said complementary offset portions.

5. An insulated support for a resistor, comprising a pair of metallic strips of U-shaped cross section spaced apart and opening toward each other, and a series of supporting members extending between said U-shaped strips having shank portions embraced by said strip and transversely bent portions for engaging the resistor, and in-

sulating material arranged between said shank members and said metallic strips. 10

In testimony whereof I affix my signature in presence of two witnesses.

FRANK KUHN.
